UNITED STATES PATENT OFFICE.

WILLIAM H. GREENLEAF, OF HARTFORD, CONNECTICUT.

LOCKING DEVICE.

1,284,890.

Specification of Letters Patent. Patented Nov. 12, 1918.

Application filed October 16, 1916. Serial No. 125,936.

To all whom it may concern:

Be it known that I, WILLIAM H. GREENLEAF, a citizen of the United States, residing at Hartford, in the county of Hartford 5 and State of Connecticut, have invented certain new and useful Improvements in Locking Devices, of which the following is a specification.

This invention relates to locking-devices, 10 the purpose of the invention being to provide an article of this character which is susceptible of inexpensive manufacture, which can be readily and quickly applied and which will securely and substantially 15 hold an object to a support, even where such an object is subjected to shocks, jars and vibration. The locking device is obviously capable of general use. It is of particular utility, however, when employed for holding 20 a clock to the dash of an automobile.

In the drawings accompanying and forming part of the present specification I have shown in detail one convenient form of embodiment of the invention which will be 25 set forth fully in the following description. I do not restrict myself to this particular disclosure; I may depart therefrom in several respects within the scope of the invention defined by the claims following said 30 description.

Referring to said drawings:

Figure 1 is a top plan view of a clock and locking means associated therewith for holding the clock to the dash represented 35 in section in said view.

Fig. 2 is a vertical section on the line 2—2 of Fig. 1, looking in the direction of the arrows.

Fig. 3 is a rear elevation of a locking 40 ring, the clock being shown by dotted lines and the ring being shown just after it has been applied.

Fig. 4 is a rear view of the parts shown in Figs. 1 and 2 with the locking-ring set.

Fig. 5 is a perspective view of the ring.

Fig. 6 is a sectional detail of a portion of the clock case, dash, bezel ring and crystal.

Fig. 7 is a detail view in section on the 50 line 7—7 of Fig. 4, looking in the direction of the arrow.

Fig. 8 is a detail view in elevation of part of the dash.

Like characters refer to like parts

throughout the several views, which are on 55 different scales.

There are parts which when mounted are subjected to considerable jars and vibrations. This applies to the clocks found on automobiles. Such a clock is generally supported by the dash of the car. I provide means whereby such an article or any other for that matter can be held securely in place against accidental movement. In Figs. 1 and 2 I have shown the case 2 of a self-winding clock. The dash 3 has a hole or perforation 3' to receive this cylindrical case. From the wall of the hole 3' the slots or keyways 3'' functioning as hereinafter set forth, extend. The clock movement is 70 not shown. I do illustrate, however, a setting arbor 4 and a binding post 5 from which the connector 6 leads. The invention, however, does not concern these features, and I mention them merely because 75 they are shown in Figs. 1 and 2. The case 2 has at its front or open side the annular flange 7 adapted to fit flatwise against the inner surface of the dash. This flange is integral with the part 2, and I find that I 80 can secure a very inexpensive construction by molding them in dies. Associated with the flange 7 is a bezel ring 8, forward of which is the crystal 9.

To hold the clock in proper relation with 85 the dash and to perform a similar function with any other suitable part and its supporting structure, a locking ring as 10 is provided. This locking ring as shown consists of oppositely disposed helical or flat 90 coiled portions 11 and 12 connected at their terminals by necks 13 and 14, the whole being in one piece. This ring 10 is preferably made of resilient material such as sheet metal which can be cut from suitable stock 95 and afterward shaped up with the aid of proper dies. The ring 10 interiorly thereof has slots 15 and 16, these slots or notches being for the reception of fins as 17 and 18 100 external of the cylindrical part and approximately opposite each other. The fins 17 and 18 are parallel with the axis of the case 2. The diametrically opposite fins 17 and 18 are slotted as at 19 at different portions in their length, the slots of the respective fins being approximately opposite. The front walls of the slot 19 are at right 105 angles to the axis of the case 2, while the

rear walls are at acute angles to the front walls. The pitch, however, of these rear walls is greater than that of the portions 11 and 12 of the locking ring, so as to present 5 detent teeth 20 of rather sharp type. Said fins 17 and 18 fit the keyways or slots 3" to prevent the case 2 from turning; said fins therefore act as keys. By slotting the fins or keys I provide on said case two series 10 of longitudinally separated locking lugs.

In mounting an article such as the clock, the cylindrical portion 2 will be passed through its opening 3', the case being held against turning in the manner set forth. 15 The ring 10 will now be applied, and this may be accomplished as follows: The center of the ring will be brought into coincidence with the axis of the case 2 and the ring will be turned if necessary so as to bring 20 the slots or notches 15 and 16 into register with the fins 17 and 18 as shown in Fig. 3. The ring will then be slipped along the fins until it is brought into register with the appropriate diametrically opposite slots 19, 25 the particular slots being determined by the thickness of the dash 3. In Fig. 1 the ring has been introduced into the two intermediate slots. After the two portions of the ring have been entered into these slots, the 30 ring will be turned in the direction of the arrow in Fig. 3. The front faces of the two portions of the ring as the latter is turned ride against the front face of the dash or equivalent support so that as the ring is 35 turned, the two portions will be jammed or wedged solidly against the rear beveled walls of the slots 19, the ring bending if it be resilient, which is the preferable construction. This action will be continued 40 until the ring can be turned no farther. To take off the ring the procedure outlined will be exactly reversed.

In some cases I can rely merely upon the resilience of the ring or the wedge-shaped 45 locking action, to prevent retractive movement of said ring. I prefer, however, to provide more positive means for this purpose, and the teeth or acute detent portions 50 to which I have referred play an office in this particular. It will be noticed that the ring 10 has on its opposite portions cuts or kerfs 21 which can be easily formed therein to produce a ratchet surface, and these are adapted to be successively entered 55 by the biting or detent teeth 20 as the ring is turned home. When the ring is properly set, the two teeth 20 will fit diametrically opposite tooth spaces 21 to positively and effectually prevent backward rotation of the 60 locking ring. To free the ring, the ring will be flexed or sprung sufficiently to carry the two tooth spaces 21 free of the teeth 20. When this is done the ring can be rotated backward in a ready, easy manner. The 65 offset connecting portions 13 and 14 which

unite the two helical operative parts 11 and 12 present a very convenient means for manipulating the ring during its application and removal.

It will be clear that the locking ring 10 70 as it is turned yieldingly engages the dash or equivalent support as 3. As a consequence the object sustained by the dash is drawn against the dash by a thrust applied thereto in a direction parallel to the axis 75 of rotation of the ring, the locking effect or thrust being in fact a wedge one. It will be understood that the locking ring 10 or analogous part can be applied or mounted or detached without completely rotating 80 it. I also depend upon a spring or wedging effect and do not bite the periphery or circumference of the object, which as already noted, is a clock. The wedging effect is in the present case applied laterally of the 85 locking ring. It is also of advantage to provide circumferential lugs which are secured by slotting the opposite fins 17 and 18. In view of the lateral engagement of the locking ring with the clock and its support 90 or equivalent parts, there is no possibility of the locking ring being crushed or distorted, which is an important point. These fins 17 and 18 divided into lugs as I have already stated, prevent positively the object 95 from turning, acting as keys. The circumferential lugs or teeth, made by dividing the fins also engage a roughened surface of the locking ring, in view of which circumstance, it is practically impossible for the latter to 100 accidentally turn backward.

What I claim is:

1. A locking ring comprising resilient helical portions and connecting portions uniting the terminals of the helical portions 105 and extending laterally therefrom.

2. A resilient locking ring having two opposite connected helical portions, one of the lateral surfaces of the helical part of the ring being roughened. 110

3. A resilient locking ring having two opposite connected helical portions, and also having ratchet teeth on one of its surfaces.

4. A resilient locking ring comprising oppositely disposed helical portions and connecting portions uniting the terminals of the helical portions, the locking ring being kerfed on one side to present a locking surface. 115

5. A resilient locking ring comprising oppositely disposed helical portions and connecting portions uniting the terminals of the helical portions, said ring being kerfed on one side to produce a multiplicity of ratchet teeth and also being oppositely slotted on its inner side adjacent the connecting portions. 120

6. The combination of a support, an object removably carried by said support, and a locking ring to surround said object and 130

- to engage said support, the locking ring being resilient and being thus adapted to yieldingly engage said support, said locking ring having means to apply a wedging effect 5 to said object to hold the same to the support as said locking ring is turned around said object, the latter having means to prevent positively backward accidental movement of the locking ring.
- 10 7. The combination of an object having external fins, the fins being slotted at different points in their length, and the slots of the respective fins being approximately opposite, and a resilient locking ring turnable 15 upon the object between diametrically opposite slots, the fin portion of the object and the ring being interlocked to prevent accidental backward turning movement of the ring.
- 20 8. The combination of an object having external fins, said fins being slotted at different points in their length and the slots of the respective fins being approximately opposite, and a resilient locking ring turn- 25 able upon the object between diametrically opposite slots, the rear walls of the slots being beveled to produce detent teeth and the adjacent surface of the locking ring being ratcheted to coöperate with the respective teeth. 30
9. The combination of an object, and a locking ring to turn on said object, the locking ring as it is turned yieldingly engaging the support of the object and applying a wedging effect to both the object and 35 the support in a direction parallel to the axis of turning movement of the ring to draw a part of the object against the support, the object having means engaging the ring to prevent positively accidental back- 40ward movement of the ring.
10. A locking ring comprising resilient helical portions inclined oppositely to each other, and connecting portions uniting the terminals of the helical portions and extending laterally from the ends of said helical portions. 45

In testimony whereof I affix my signature in the presence of two witnesses.

WILLIAM H. GREENLEAF.
